 LEATHER CUTTING MACHINE.
 APPLICATION FILED NOV. 24, 1900.

2 SHEETS—SHEET 2.

UNITED STATES PATENT OFFICE.

JOHN W. KENNINGTON, OF DEDHAM, MASSACHUSETTS.

LEATHER-CUTTING MACHINE.

SPECIFICATION forming part of Letters Patent No. 783,725, dated February 28, 1905.

Application filed November 24, 1900. Serial No. 37,612.

To all whom it may concern:

Be it known that I, JOHN W. KENNINGTON, a citizen of the United States, residing at Dedham, in the county of Norfolk, State of Massachusetts, have invented a certain new and useful Improvement in Leather-Cutting Machines, of which the following is a specification, reference being had therein to the accompanying drawings.

10 The invention relates to leather-cutting machines of that class in which the leather is placed upon a hollow die attached to the frame of the machine with its cutting edge uppermost and is forced down upon the same by a moving part of the mechanism. The present aim is to produce a mechanism combining simplicity and lightness with great power and having a rapid and certain action. Another object is to preclude the possibility of accidental operation of the machine and consequent injury to the operator. Further practical advantages of the device will be referred to in the course of the following description.

In the accompanying drawings I have shown 25 the invention in the best form so far produced by me.

The essential characteristics of the invention will be more particularly pointed out and defined in the claims at the close of this specification.

30 In the drawings, Figure 1 is a side view of the machine, showing several parts thereof in section, the hammer being shown in full lines in retracted position and in dotted lines in striking position. Fig. 2 is a plan view of the same. Fig. 3 is a front elevation of the same, the hammer being shown in striking position. Fig. 4 is a view showing separately the controlling-treadle and its adjuncts.

40 The table supporting the moving parts of the machine is designated 1, one of the legs supporting the same being shown and being designated 2.

45 3 3 are brackets bolted side by side near the rear edge of the table and projecting upward therefrom, the upper ends of these brackets being provided with bearings 4 4. In these bearings are received the journals 5 of an oscillating frame 6, which latter extends for- 50 ward over the table and itself carries near its

front end bearings 7 7 for the journals 8 of an oscillating hammer 9.

The frame 6 is arranged to oscillate only through a very small arc, the purpose of such oscillation, as will presently be more particularly explained, being to bring the hammer into action. The hammer itself, on the other hand, when brought into action oscillates through an arc of nearly one hundred and eighty degrees, it being brought into the position indicated in dotted lines in Fig. 1 in order to strike down upon the leather placed upon the die, which latter is herein designated 10. The die is supported in a novel manner, as follows: 101 is a die-block which is attached 60 to the table 1 by bolts 102 passing through ears 103 at the sides of the block and entering tapped holes in the table. The die-block and table have apertures corresponding with and forming a continuation of the open interior of 70 the die to permit of the escape of the heel-pieces cut from the leather. At the front and back of the block, on the upper face thereof, are ribs 104 105, which are in line with each other and which are dovetailed in cross-section. Corresponding dovetailed channels are formed through the front and rear walls of the die, the latter thus being adapted to slip onto the ribs and to be brought accurately to place over the aperture in the block. Pins 80 75 106 are then inserted into vertical holes in the ribs immediately outside the die, securing the latter firmly in its proper position. With this arrangement the die is prevented from working loose under the repeated impact of 85 the hammer. At the same time there is no difficulty in removing the die for sharpening the same or for other desired purposes, the only preliminary step being removal of the pins 106. 90

The force exerted by the hammer upon the leather is not a mere pressure, as in the case of most other leather-cutting machines, but is percussive in its nature. The mechanism hereinafter described has been devised with 95 the general purpose of putting the hammer fully under the control of the operator in certain of its movements and in causing the hammer to operate correctly automatically in other particulars, whereby all contingencies are met 100

and the advantages hereinabove set forth are secured.

The hub of the hammer is formed as a segment 11, which is concentric with the pivot 8. 5 Directly below the said pivot, beneath the table 1, is supported in bearings 12 a shaft 13, carrying a pulley 14. The periphery of the pulley is covered with leather or some other material having a friction-surface, as indicated 10 at 15. The diameters of the pulley 14 and segment 11 are so proportioned that when the frame 6 is in its normal or raised position the two said parts will be separated from contact with each other a slight distance--say the 15 thirty-second of an inch. A constant rotation is given to the pulley 14 in the direction indicated by the arrow thereon, and when the frame 6 is drawn downward, as will presently be explained, the segment 11 is brought into 20 contact with the pulley and is caused to rotate, and thereby to carry the hammer over into its dotted-line position in Fig. 1. The force of the blow delivered upon the die by the hammer is governed by the degree of frictional 25 engagement between the segment and pulley, which in turn is regulated by the degree of force with which the frame 6 is depressed by the operator.

The striking-face of the hammer is designated 91. It is made detachable in order that it may be replaced when worn out or changed for a face of different contour. The striking-face in use at any given time is one corresponding in contour with the die, but slightly 30 larger than the latter, so as properly to cut the leather, while safely permitting the operator in holding the leather to place his fingers very close to the cutting edge of the die. This construction avoids waste of material in cutting, 35 inasmuch as the operator without danger may hold on the die a piece of leather hardly larger than the die itself. As indicated in Fig. 1, a spindle 92 runs through the hammer-body, one end of the said spindle screwing into the striking-face 91 from the rear side of the latter and the other end being screw-threaded to receive a nut 93. A transverse slot is formed in the spindle and hammer-body to receive the key 94. A set-screw 95 bears against the key 40 and retains it in any desired position. The key having thus been set, the nut 93 is turned up solidly, thereby securing the striking-face 91 at the required adjustment. A pin 96 projects from the rear side of the striking-face 45 and enters a hole in the hammer-body to prevent the striking-face from rotating and thereby becoming loose, while not interfering with the described adjustment of the latter. When the die becomes worn away, the nut 93 and set- 50 screw 95 are loosened, the key is driven outward to the required extent, and the parts are again set up.

To hold the frame 6 normally in its upper position, I employ one or more spiral springs 65 16, each surrounding a rod 17, the lower por-

tion of said rod being fitted within a tubular screw-threaded boss 18, cast integral with the table. Each rod 17 passes through a vertical hole in the frame 6 and is provided with check-nuts 20 and 21 on the upper threaded end 70 thereof, whereby the upward motion of the frame is limited. A check-nut 22 is also provided on each rod to retain the latter from coming loose in the boss 18. As will be seen, the spiral spring 16 is confined between the 75 check-nut 22 and the frame 6.

In order to produce the depression of the frame 6, there is provided an actuating-rod 23, the upper end of which is pivoted at 24, Fig. 1, to the tail of a hook 25, which hook in 80 turn is pivoted at 26 between forwardly-projecting ears 27 on the frame 6. The hook 25 engages with the upper end 28 of a sliding bolt 29, mounted in the frame 6. Normally the hook 25 is prevented from turning on its 85 pivot 26 by reason of its engagement with the bolt 29, as will be clearly evident from Fig. 1 of the drawings. So long as this is the case the pivot 24 is held in a fixed relation to the frame 6, and a pull on the actuating-rod 23 90 will consequently depress the frame and hold it depressed so long as the hook and bolt are in engagement with each other. When, however, the bolt is disengaged from the hook, the frame will be free to rise irrespective of 95 the action of the rod 23. The actuating-rod is pivoted at its lower extremity 231 to a foot-treadle 232, Fig. 4, mounted on rod 233, which is fixed at its ends in the frame of the machine. The treadle is extended rearward of its pivot 100 and is provided on such extension with a weight 239. The weight will be made sufficient to normally produce an upward thrust upon the actuating-rod 23. As has already 105 been explained, the depression of the frame 6 by means of the actuating-rod brings the segment into contact with the leather-covered periphery of the pulley and causes the hammer to be actuated to strike a blow upon the die. 110

In order to allow of the separation of the segment from the pulley at the moment when the blow is struck, means are provided for retracting the bolt, and thereby disengaging the hook and allowing the hook to turn freely on 115 its pivot. To accomplish this object, I provide on the shank of the hammer a projection 30, which is arranged to strike a head 31, affixed by a pin 32 or other suitable means on the lower end of the bolt 29. Herein the projection 30 is shown as arranged to actuate the bolt 29 at approximately the instant when the hammer has delivered its blow. (See dotted lines in Fig. 1.) The bolt is surrounded by a spiral spring 33, which serves to hold its upper end projected, as shown in Fig. 1, into position to be engaged by the hook 25. The upper portion of the bore 331, in which the bolt slides, is enlarged beyond the diameter of the bolt sufficiently to accommodate the 120 125 130

said spring 33, and the latter is confined between a shoulder on the upper end of the bolt and the bottom of the said enlarged portion of the bore.

5. In order to provide for the proper retraction of the hammer, a rod 34 is employed, the upper end of which is provided with a pin 35, which projects through a segmental slot 351 in an arm 36, attached to one of the journals 8. The pin is 10 provided with a washer 352 and check-nut 353 to retain it in the slot, but the said pin is loose in the slot. The rod passes loosely through a sleeve 37, which is journaled in ears 38, depending from the table 1. The bore in the 15 sleeve is slightly flared at top and bottom to allow a free reciprocation of the rod through it. Below the sleeve 37 a spiral spring 39 is slipped upon the rod and is confined thereon by a collar 40. Above the sleeve 37 the rod 20 has a shoulder 371, of larger diameter than the bore of the sleeve, whereby the spring 39 is prevented from retracting the rod any farther than its indicated position in Fig. 1. A filler-block 42, of hardened metal, is inserted in the 25 upper end of the slot 351 and is retained therein by the bolt 421, washer 422, and nut 423, the said bolt 421 passing through a hole in the filler-block. When the hammer is thrown forward, the rod 34 remains inactive until the 30 lower end 355 of the slot 351 comes into contact with the pin 35. The rod then is drawn upward through the remaining traverse of the arm 36, the spiral spring 39 thereby being compressed. As soon as the hammer has 35 delivered its blow the reaction of the spring draws down the rod until the shoulder 371 makes contact with the sleeve 37. This retracts the hammer to a point beyond a vertical position, from whence it falls backward by 40 reason of its own weight and momentum into the completely-retracted position of Fig. 1, it being positively-arrested by contact of the filler-block 42 with the pin 35.

In order to check the hammer when it is retracted and prevent the filler-block from striking the pin too heavily, a hook 45 is provided, 45 co-operating with a lug 46, formed upon the arm 36. The hook 45 is supported, but without being retained from endwise motion, by 50 resting in an upwardly-projecting bracket 47, affixed to the table 1. The hook is attached to the end of a rod 48, extending rearward through a hole 49 in the web 50 of the bracket 3. The rod 48 passes through a block 51 of 55 rubber or the like and is provided on its rear end with a disk or cap 52 and check-nut 53. When the hammer has nearly reached its most retracted position, the lug 46 comes into forcible contact with the hook 45 and its motion is 60 checked thereby, the concussion being taken up by the rubber block 51. As already explained, a positive stop is provided in the contact of the filler-block 42 with the pin 35. As shown in Fig. 1, the reaction of the rubber 65 block 51 springs the filler-block somewhat

away from the pin after such contact has occurred. Enough vertical clearance is left between the lug 46 and shank of the hook to permit of the slight depression of the frame 6 which occurs when the hammer is thrown into 70 action.

In order to prevent the hammer from rebounding after it has been retracted, I provide a second hook 54, which projects upward just back of the lug 46 through a slot 55 in 75 the body of the hook 45. The hook 54 is formed on the end of an arm 56, pivoted at 57 to ears 58 on the table 1. The said hook has its upper surface beveled off, so that in the retraction of the hammer the lug pushes aside 80 the hook, the latter snapping back into place behind it. The arm 56 is normally held up-raised by a blade-spring 581, attached by a screw 59 to the table. Upon the frame 6 there is attached by screws 60 a push-rod 61, provided with an L-shaped bend 62 at its lower end, which bend projects over the arm 56, on which the hook 54 is carried. When, therefore, the frame 6 is depressed, the push-rod 61 depresses the arm 56 and carries the hook 85 90 95 54 downward out of the way of the lug 46. This action takes place while the segment 11 is being brought into contact with the pulley 14, so that at the instant when such contact is actually made the hammer is free to be thrown forward against the leather on the die.

By the presence of the hook 54 the hammer is prevented from being accidentally actuated in any other mode than by depression of the treadle connected with the actuating-rod 23. 100 It is only upon the downward movement of the frame 6 and pusher-rod 61 that the said hook can be withdrawn from the path of the lug 46. Thus if a scrap of leather were to fall upon the periphery of the pulley and were 105 carried through between the pulley and segment 11, thus making undesired engagement between them, the hammer would be prevented from being thrown by the presence of the hook 54 in the path of movement of the 110 lug 46.

An important part of the mechanism is a post 63, attached by bolts 64 to the table 1 at a point between the die 10 and the frame 6. A corresponding boss 641 is formed on the 115 shank of the hammer. The post is of a height to be struck by the boss 641, while there is still a slight clearance between the hammer-head and the die. Furthermore, the projection 30 is so placed that at the time the boss 120 641 strikes the post the bolt 29 will have been completely retracted from engagement with the hook 25, the frame 6 being thereby released from downward pressure. As a consequence of the foregoing construction when 125 the contact of the boss 641 with the post 63 occurs the latter will act as a fulcrum, the hammer-head continuing downward into actual contact with the die, while the hub of the hammer simultaneously kicks up and sepa- 130

rates the segment 11 from the pulley 14. The motion just described, which is resisted at the hammer-head by the toughness of the leather being cut and at the hammer-hub by the inertia of the frame 6 and the tension of the spring 39, causes the momentum of the hammer to be completely expended, thus bringing it to a dead-rest at the instant the leather has been completely severed by the die. By 10 this action the hammer is permitted to be quickly and easily returned to its initial position under the action of the spring 39.

In order to regulate automatically the degree of pressure of the segment 11 upon the 15 pulley when the treadle is depressed, I provide a rod 235, depending from a cross-iron 236 on the frame of the machine and having a hooked lower end 237, in which the treadle plays. The upper end of the rod 235 is screw-threaded and passes loosely through a hole in the cross-iron 236.

238 238 are adjustment-nuts above and below the cross-iron. By means of these nuts the hooked extremity 237 may be raised or 25 lowered to permit of more or less depression of the treadle, and hence of a predetermined greater or less degree of contact between the pulley and segment. Thus the accuracy of 30 operation of the hammer is rendered independent of the skill of the particular operator who is running the machine.

What I claim is—

1. In a leather-cutting machine, in combination, a relatively fixed die, against the cutting edge of which the leather to be cut is held, a movable hammer acting by its impact upon the leather resting against said die to drive the leather on to the die and thereby effect the cutting, and mechanism to impart 35 momentum to said hammer and release it to its own momentum, substantially as described.

2. In a leather-cutting machine, in combination, a relatively fixed die, against the cutting edge of which the leather to be cut is held, a movable hammer acting by its impact 45 upon the leather resting against said die to drive the leather on to the die and thereby effect the cutting, mechanism to impart momentum to said hammer and release it to its 50 own momentum, and, mechanism acting automatically to return said hammer to its starting position and there hold it latched against rebound, substantially as described.

3. In a leather-cutting machine, in combination, the movable hammer, power-actuating devices for communicating movement to said hammer and then releasing it to make the effective part of its stroke under acquired 55 momentum, controlling devices whereby at the will of the operator the said hammer is brought into action, and a die co-operating with said hammer, substantially as described.

4. In a leather-cutting machine, in combination, the movable hammer, power-actuating 60 devices for communicating movement to

said hammer and then releasing the same to make the effective part of its stroke under acquired momentum, means to hold said power-actuating devices normally disconnected, controlling means whereby at the will 70 of the operator the said devices are operatively connected to actuate the said hammer, and a die coacting with said hammer, substantially as described.

5. In a leather-cutting machine, in combination, the movable hammer, power-actuating devices for communicating movement to said hammer and then releasing the same to make the effective part of its stroke under acquired momentum, means to hold said power-actuating devices normally disconnected, controlling means whereby at the will 80 of the operator the said devices are operatively connected to actuate the said hammer, a die coacting with said hammer, and mechanism acting automatically to return said hammer to its starting position and there hold it latched against rebound, substantially as described.

6. In a leather-cutting machine, the combination of a movable hammer, mechanism to impart momentum thereto, devices for disconnecting the said mechanism from the hammer at a predetermined point in the traverse of the latter, and a die arranged in connection 95 with the hammer, to be caused to penetrate the leather by the momentum thereof.

7. In a leather-cutting machine, the combination of a movable hammer, a movable frame in which the hammer is mounted, mechanism 100 for imparting momentum to the hammer normally disconnected therefrom but brought into engagement therewith by motion of the frame, devices for moving the frame, means for releasing such devices from the frame at 105 a predetermined point in the traverse of the hammer and thereby permitting the frame to return to its initial position, and a die arranged in connection with the hammer, to be caused to penetrate the leather by the momentum thereof.

8. In a leather-cutting machine, the combination of a movable hammer, a movable frame in which the hammer is mounted, mechanism for imparting momentum to the hammer, 115 normally disconnected therefrom but brought into engagement therewith by motion of the frame, devices for moving the frame, means for releasing such devices from the frame at a predetermined point in the traverse of the 120 hammer, a stop located in the path of the hammer and affording a fulcrum therefor, whereby upon such release, a portion of the momentum of the hammer is expended in returning the frame to its initial position and 125 disconnecting the hammer from the momentum-producing mechanism, and a die arranged in connection with the hammer, to be caused to penetrate the leather by the momentum thereof.

9. In a leather-cutting machine, the combination of a pivoted hammer, a segment on the hub thereof, a pulley, means to rotate the pulley, means to bring the pulley and segment into engagement with each other, and a die arranged in connection with the hammer, to be caused to penetrate the leather by the momentum thereof.
10. In a leather-cutting machine, the combination of a pivoted hammer, a movable frame carrying the same, manually-operable devices for moving the frame, releasably connected with the latter, means carried by the hammer for releasing such devices at a predetermined point in the traverse of the hammer, a segment on the hub of the hammer, a rotating pulley into contact with which the segment is brought by the movement of the frame, and a die arranged in connection with the hammer, to be caused to penetrate the leather by the momentum thereof.
11. In a leather-cutting machine, the combination of a pivoted hammer, a movable frame carrying the same, a rod manually operated for moving the frame, connections between the rod and frame comprising a pivoted hook and sliding bolt, a projection on the hammer for retracting the bolt, a segment on the hub of the hammer, a rotating pulley into contact with which the segment is brought by the movement of the frame, and a die arranged in connection with the hammer, to be caused to penetrate the leather by the momentum thereof.
12. In a leather-cutting machine, the combination of a pivoted hammer, a movable frame carrying the same, means to impart momentum to the hammer when the frame is depressed, a post in the path of the shank of the hammer, serving as a fulcrum on which the continued rotation of the hammer takes place, a portion of the momentum of the hammer operating to return the frame to its initial position, and a die arranged in connection with the hammer, to be caused to penetrate the leather by the momentum thereof.
13. In a leather-cutting machine, the combination of a movable hammer, means to impart momentum to the hammer, means to retract the hammer after it has delivered its blow, a stop to limit such retraction, and a second stop movably mounted to permit of such retraction while preventing recoil of the hammer.
14. In a leather-cutting machine, the combination of a movable hammer, means to impart momentum to the hammer, a lug affixed to the hammer, a spring-held hook in the path of the lug to arrest the retraction of the hammer, a second movable hook in the path of the lug to prevent rebound of the hammer.
15. In a leather-cutting machine, the combination of a movable hammer, a movable frame carrying the hammer, mechanism for imparting momentum to the hammer when the frame
- is depressed, a movable stop to prevent recoil of the hammer after the latter has been retracted, and a pusher on the frame adapted for engagement with the stop when the frame is depressed, to remove the stop from the path of the lug and permit the momentum-imparting mechanism to actuate the hammer.
16. In a leather-cutting machine, the combination of a movable hammer, a movable frame carrying the hammer, mechanism for imparting momentum to the hammer when the frame is depressed, a movable stop to prevent actuation of the hammer, and means connected with the frame for withdrawing the stop from its operative position when the frame is depressed, and permitting the hammer to be actuated.
17. In a leather-cutting machine, the combination of a movable hammer, a movable frame carrying the hammer, mechanism for imparting momentum to the hammer when the frame is depressed, a sliding bolt on the frame, a pivoted hook engaging with the bolt, an actuating member for depressing the frame, attached to the hook, and coöperating members on the bolt and hammer for retracting the bolt at a predetermined point in the traverse of the hammer.
18. In a leather-cutting machine, in combination, a swinging hammer, mechanism for imparting momentum to the hammer, a rod having pin-and-slot connection with said hammer whereby a certain amount of relative movement is permitted, a guide through which said rod is passed, and a spring connected with said rod for retracting the same, substantially as described.
19. In a leather-cutting machine, the combination of a movable hammer, mechanism for imparting momentum to the hammer, an arm on the hammer having a slot therein, a rod having a pin playing in the slot, and having a shoulder, a journaled sleeve through which the rod slides, and a spring for retracting the rod and bringing the shoulder thereof into contact with the sleeve, thereby partly retracting the hammer by the force of the spring and allowing the remaining part of the retraction of the hammer to occur independently of the spring.
20. In a leather-cutting machine, in combination, a cutting-die, a hammer, a train of automatic actuating connections for operating the said hammer by momentum, said train being normally broken or disconnected to leave the hammer inoperative, and means to close the break in the said train to occasion the operation of the hammer, substantially as described.
21. In a leather-cutting machine, in combination, a cutting-die, a hammer, means to retract the hammer after having been actuated to effect a cutting, means to lock the hammer in its retracted position, a train of automatic actuating connections for imparting momen-

tum to the said hammer normally broken or disconnected to render the hammer inoperative, and means to close the break in the said train to occasion the operation of the hammer 5 and simultaneously unlatch the said locking means to release the hammer, substantially as described.

22. In a leather-cutting machine, in combination, a cutting-die, a hammer, means to actuate the said hammer embracing a treadle whereby such means is rendered operative at the will of the attendant upon the machine to occasion a stroke of the hammer, and a spring 15 to retract the hammer to its normal position of rest, substantially as described.

23. In a leather-cutting machine, the combination of a pivoted hammer, a segment on the hub thereof, a pulley, means to rotate the pulley, manually-operable devices for bringing the segment into contact with the pulley, and an adjustable stop for limiting the motion of such devices and thereby automatically limiting the degree of frictional pressure between the segment and pulley. 20

In testimony whereof I affix my signature in 25 presence of two witnesses.

JOHN W. KENNINGTON.
